US00D558760S

(12) **United States Design Patent** (10) **Patent No.:** **US D558,760 S**
(45) **Date of Patent:** ** *Jan. 1, 2008

(54) **DATA COLLECTION DEVICE**

(75) Inventors: **Timothy R. Fitch**, Syracuse, NY (US);
Brian V. Conti, Matthews, NC (US)

(73) Assignee: **Hand Held Products, Inc.**, Skaneateles Falls, NY (US)

(**) Term: **14 Years**

(21) Appl. No.: **29/212,930**

(22) Filed: **Sep. 9, 2004**

Related U.S. Application Data

(63) Continuation of application No. 10/754,653, filed on Jan. 9, 2004.

(51) **LOC (8) Cl.** **14-02**

(52) **U.S. Cl.** **D14/346**

(58) **Field of Classification Search** D14/341-347;
D18/1, 2, 7; 235/145 A, 145 R, 462.46;

(57) **CLAIM**

The ornamental design for a data collection device, as shown and described.

DESCRIPTION

FIG. 1 is a top perspective view of a data collection device according to the invention;

FIG. 2 is a bottom perspective view of the data collection device shown in FIG. 1;

FIG. 3 is a top view of the data collection device shown in FIG. 1;

FIG. 4 is a bottom view of the data collection device shown in FIG. 1;

FIG. 5 is a rear view of the data collection device shown in FIG. 1;

FIG. 6 is a front view of the data collection device shown in FIG. 1;

FIG. 7 is a first side view of the data collection device shown in FIG. 1; and,

FIG. 8 is a second side view of the data collection device shown in FIG. 1.

The broken lines of the drawings are for illustrative purposes and form no part of the claimed design.

1 Claim, 6 Drawing Sheets
